HAMPER

Herman Weintraub, Cedarhurst, and Carl Fuerst,
 Bronx, N. Y., assignors to Gleitsman's, Inc.,
 Long Island City, N. Y., a corporation of New
 York

Application May 5, 1949, Serial No. 91,456

2 Claims. (Cl. 232—1)

1

This invention relates to clothes hampers or the like.

It is an object of the present invention to provide a clothes hamper of a type which may permanently be suspended on any suitable upright support, such as a door, for instance, and from which the contents may be removed without having to handle the latter.

It is a more specific object of the present invention to provide a clothes hamper of this type which has an open back and is normally closed thereat by the support on which it is so hinged mounted with its top as to require mere outward swinging of the hamper at its closed bottom in order to permit the contents to drop by gravity through the open back thereof.

It is another object of the present invention to provide a clothes hamper of this type which will automatically become latched in either open or closed position, and which will be released in either position on simple manipulation thereof.

It is another object of the present invention to provide a clothes hamper of this type which will become latched in its closed position more firmly the heavier its contents is, and which will be released in its open position with such ease as to require to that end a mere push against the bottom thereof.

It is another object of the present invention to construct the hamper simply, yet sturdy, and so that it readily lends itself to efficient and inexpensive mass production.

The above and other objects, features and advantages of the present invention will be more fully understood from the following description considered in connection with the accompanying 35 illustrative drawings.

In the drawings:

Fig. 1 is a perspective view of a clothes hamper embodying the present invention;

Fig. 2 is another perspective view of the hamper, shown in position for the removal of the contents therefrom;

Figs. 3 and 4 are enlarged fragmentary sections taken on the lines 3—3 and 4—4, respectively, 45 of Figs. 1 and 2, respectively;

Figs. 5 and 6 are enlarged fragmentary sections taken on the lines 5—5 and 6—6, respectively, of Figs. 1 and 2, respectively;

Fig. 7 is an enlarged fragmentary section taken 50 on the line 7—7 of Fig. 5;

Fig. 8 is a section similar to Fig. 6, showing a modification of the hamper; and

Fig. 9 is a section similar to Fig. 5, showing a further modification of the hamper.

Referring to the drawings, and more particularly to Figs. 1 to 4 thereof, the reference numeral 10 designates a hamper which is hingedly suspended on any suitable upright support, and which is characterized by having an open back 60

2

which, in the closed position of the hamper, is normally closed by the support on which the hamper is suspended in order that the latter may retain its contents of dirty clothes, for instance. The hamper 10 is, in the present instance, shown hingedly suspended at its top on a swinging door 12 through intermediation of suitable brackets 14.

The open-back hamper 10, which may be of any suitable construction, is also open at the top and comprises, in the present instance, closed front, side and bottom walls 16, 18 and 20, respectively. The open top of the hamper may normally be closed by a hinged cover 22. The front and side walls 16 and 18 of the hamper may, as shown in the present instance, be made of preferably fibrous wicker work which is in any suitable manner secured with its margins in a skeleton frame 26 that may conveniently be made from side channels 28 and connecting top and bottom channels 30. The bottom wall 20 of the hamper 10 may be of any suitable solid material, such as fibre board, for instance, which may conveniently be secured in place by the inwardly turned flange 32 of the bottom channel 30 (Fig. 3). The cover 22 may be hinged on a rod 34 on which the hamper itself is preferably suspended by means of hooks 36 which are carried in any suitable manner by the upper ends of the side channels 28. For the suspension of the hamper 10 on the door 12, the opposite ends of the rod 34 are mounted in the brackets 14 which are, in turn, suitably mounted at 40 on the door 12. More particularly, the opposite ends of the rod 34 extend, for a reason herein-after described, through elongated slots 42 in the opposite brackets 14, respectively. In the closed position of the hamper as shown in Figs. 1 and 3, the open-back 44 thereof is closed by the door 12 on which the hamper is suspended, so that the contents will not escape therefrom.

In order that the hamper 10 may not swing open when packing clothes therein or when the door is swung, provisions are made to latch the hamper in its closed position against opening. To this end, there is rotatably carried, preferably on each end of the rod 34, a link arm 46 which is also connected with the adjacent side channel 28 as by a rivet 48, for instance. Each link arm 46 carries intermediate its ends a pin 50 which projects into a slot 52 in the adjacent mounting bracket 14 (Fig. 5). The slot 52 in each mounting bracket 14 is so designed as to cooperate with the pin 50 on the adjacent link arm 46 in latching the hamper 10 not only in its closed position (Fig. 1), but also in its open position (Fig. 2). To this end, each slot 52 is provided with downwardly directed ends 54 and 56, of which the slot end 54 is inclined to the door 12 so as to have a cam action on the pin 50 of the adjacent link

arm 46 in forcing the hamper 10 with its open back against the door 12 (Fig. 5). The opposite end 56 of each slot 52 cooperates with the pin 50 on the adjacent link arm 46 in latching the hamper in its open position (Fig. 6). Thus, in order to release the hamper in either of its positions from interlatch with the mounting brackets 14, the former will have to be raised in order to bring the pins 50 of the link arms 46 into alignment with the median portions 60 of the slots 52, as will be readily understood. Lifting of the hamper 10 to this end is permitted due to the provision of the elongated slots 42 in the mounting brackets 14 in which the respective ends of the rod 34 act as floating pivots for the hamper. The outer ends of the rod 34 are preferably threaded to receive nuts 57, respectively, in order to prevent axial removal of the rod 34 from the mounting brackets 14.

Preferably, the end 56 of each slot 52 extends substantially parallel to the adjacent link arm 46 in the open position, of the hamper (Fig. 6), so as to facilitate the release of the hamper in its open position, preferably to the extent where a thrust against the bottom end thereof, as occasioned, for instance, when the open hamper hits against some obstacle on swinging the door, closes the hamper.

Fig. 8 shows a modification of the hamper, designed to latch the hamper in its closed position only. To this end, the slots 52 in the mounting brackets 14 are formed with the inclined ends 54 only, as will be readily understood.

Fig. 9 shows a further modification in which the hamper 10 is non-floatingly hinged with its rod 34 in any conventional mounting brackets 10, and the bottom of the hamper is, in the present instance, provided with a projection 72 which cooperates with a latch spring 74 on the door 12 in releasably latching the hamper in its closed position. As in the case of the modified hamper shown in Fig. 8, no provisions are made for latching the instant modified hamper in its open position.

In use, dirty clothes are dropped into either one of the hampers shown when in their closed position. To remove the collected clothes from the hamper, the latter is swung into its open position as previously described, whereupon the clothes will drop through the open back of the hamper onto the floor or into a container, such as a basket, placed underneath the hamper.

In suspending the hamper on any suitable upright support, the former requires no floor space and is, therefore, particularly well suited for installation in small or crowded living quarters. Further, in suspending the hamper on a door, the former occupies a space which for obvious reasons is never used for other furnishings that require floor space, wherefore the installation of the hamper will never raise any problem even under most adverse space conditions.

While we have shown and described the preferred embodiments of our invention, it will be understood that various changes may be made in the present invention without departing from the underlying idea or principles of the invention within the scope of the appended claims.

Having thus described our invention, what we claim and desire to secure by Letters Patent, is:

1. A hamper for installation on any existing upright support such as a door, said hamper comprising an open-back and closed-bottom receptacle having remote from said bottom an opening other than said open back for the introduction into the hamper of the contents thereof, said

receptacle being devoid of any cover provisions on the hamper for said open back, brackets on the opposite sides, respectively, and adjacent the top of said receptacle, said brackets being mountable on said upright support and having an elongated slot and a cam slot in spaced relation, said latter slot having downwardly directed inclined ends, pin means carried by said receptacle and positioned in said cam slot, mounting provisions carried by said receptacle and extending through said elongated slots, said brackets floatingly hingedly carrying said receptacle for bodily movement in a plane parallel to said upright support and for swinging movement from a normal position in which its open back is closed by said upright support into a forward position in which its open-back is spaced from said upright support through the cooperative association of said mounting provisions and said elongated slots, said pin means being adapted to be received in one of said cam slot inclined ends for latching said receptacle in said normal position and said pin means being adapted to be received in the other one of said cam slot inclined ends for latching said receptacle in said forward position.

2. A hamper for installation on any existing upright support such as a door, said hamper comprising an open-back and closed-bottom receptacle having remote from said bottom an opening other than said open back for the introduction into the hamper of the contents thereof, said receptacle being devoid of any cover provisions on the hamper for said open back, brackets on the opposite sides, respectively, and adjacent the top of said receptacle, said brackets being mountable on said upright support and each of said brackets having an elongated slot, mounting provisions carried by said receptacle and extending through said elongated slots, said brackets floatingly hingedly carrying said receptacle for bodily movement in a plane parallel to said upright support and for swinging movement from a normal position in which its open back is closed by said upright support into a forward position in which its open back is spaced from said upright support through the cooperative association of said mounting provisions and said elongated slots, and means for latching said receptacle in said normal and forward positions, said means comprising pin means carried by said receptacle, at least one of said brackets having a cam slot spaced from said elongated slot, said cam slot having downwardly directed inclined ends, said pin means being positioned in said cam slot and adapted to be received in one of said cam slot inclined ends for latching said receptacle in said normal position and in the other one of said cam slot inclined ends for locking said receptacle in said forward position.
